UNITED STATES PATENT OFFICE.

CLARENCE R. GILLETT, OF CHICAGO, ILLINOIS, ASSIGNOR TO THE MAGIC LIGHT COMPANY, OF SAME PLACE.

DESIGN FOR A LAMP-FIXTURE.

SPECIFICATION forming part of Design No. 33,291, dated October 2, 1900.

Application filed September 7, 1900. Serial No. 29,344. Term of patent 14 years.

To all whom it may concern:

Be it known that I, CLARENCE R. GILLETT, a resident of Chicago, in the county of Cook and State of Illinois, have invented and produced a new and original Design for Lamp-Fixtures, of which the following is a specification, reference being had to the accompanying drawing, forming a part thereof.

The drawing is a view in side elevation of the lower fixture embodying my design.

As shown in the drawing, the leading or most characteristic feature of my design consists in a lamp-fixture comprising a central vertical bar A, having short branches B B' at its lower end. Supported by these branches are the U-shaped frames D D', as shown. From the upper ends of the U-shaped frames D D' project in line the horizontal tubular portions E E' and e e'. As shown, the verti-

cal rod D is provided at its upper end with a 20 cylindrical protuberance F and at its lower end with a depending spear-shaped scroll G, which is located between the frames D D'. The upper ends of the inner legs of the frames D D' are provided with small branched scrolls 25 H H' and the upper ends of the outer legs of the frames D D' with the large inwardly-curved branched scrolls I I'.

Having thus described my invention, what I claim as new, and desire to secure by Letters 30 Patent, is—

The design for a lamp-fixture, substantially as herein shown and described.

CLARENCE R. GILLETT.
